(No Model.)

W. BUTTERFIELD.

HARVESTER REEL.

No. 366,301.

Patented July 12, 1887.

UNITED STATES PATENT OFFICE.

WILLIAM BUTTERFIELD, OF AUBURN, NEW YORK, ASSIGNOR TO D. M. OSBORNE & COMPANY, OF SAME PLACE.

HARVESTER-REEL.

SPECIFICATION forming part of Letters Patent No. 366,301, dated July 12, 1887.

Application filed March 2, 1887. Serial No. 229,425. (No model.)

To all whom it may concern:

Be it known that I, WILLIAM BUTTERFIELD, of Auburn, in the county of Cayuga and State of New York, have invented certain Improvements in Harvester-Reels, of which the following is a specification.

This invention has reference to that class of reels in which the reel-shaft is supported in bearings on a crank arm or arms extending from a rock-shaft, so that by turning said rock-shaft the reel may be raised or lowered, and the aims of the invention are to provide a single mechanism for effecting the adjustment of the rock-shaft by means of a hand-lever, which shall remain at all times within convenient reach of the driver; and to this end it consists in the combination, with the lever and rock-shaft, of certain intermediate parts, which will be hereinafter described.

In the accompanying drawings, Figure 1 represents a side elevation of my reel supporting and adjusting mechanism. Fig. 2 is a front elevation of the same. Fig. 3 is a side view of the rack-plate through which the parts are held in position. Fig. 4 is an edge view of the said plate. Fig. 5 is a side view of the plate attached to the hand-lever and the sliding dogs thereon.

Referring to the drawings, A represents a rock-shaft mounted in stationary bearings B, and provided at one end with a crank-arm, A', on which are mounted, in the usual manner, the bearings for the reel-shaft C. Under this arrangement the entire weight of the reel is carried by a crank-arm, and the vertical adjustment of the reel secured by turning the rock-shaft in its bearings, thereby causing the crank-arm to rise and fall. These parts are of ordinary construction, familiar to every person skilled in the art, and are not claimed as of the present invention.

In applying my improvement I fix rigidly upon the rock-shaft a sector-plate, D, provided, at its periphery in one edge, with a series of notches, a, and in the opposite edge with a less number of notches, b. Adjacent to this plate I pivot to a stationary plate, E, or other suitable support, a locking-dog, F, provided at its upper end with a tooth, e, which may engage in one or another of the notches a, so as to lock the plate D firmly in position, and thus hold

the rock-shaft and reel in the different positions demanded. The upper end of this locking-arm F is provided with a curved slot, d, for a purpose presently to be explained. I next provide a hand-lever, G, and bolt firmly to its lower end a supporting-plate, H, which is arranged to turn freely around the rock-shaft, except when locked in position. In this plate I mount a sliding dog, I, having at one end a stud, e, which enters the slot d of the locking-arm F. I also mount in the plate H a second sliding dog, K, arranged to engage the notches b of the plate D. The two dogs are urged downward by means of springs f, and are released at the will of the operator by operating-rod 65 extending from them to the respective thumb-levers g and h, mounted on the upper end of the hand-lever. The parts stand nearly in the position represented in Fig. 1, the arm F being 70 in engagement with the plate D and serving to hold the reel rigidly in position, while at the same time the dog K, seated in one of the notches b of the plate D, prevents the hand-lever from falling.

When it is required to raise or lower the reel, the attendant actuates the thumb-latch g, which, through the intermediate parts, disengages the arm F from the plate D, thus releasing the reel, which is now sustained through 80 the plate D and dog I by the hand-lever. The operator, raising or lowering the hand-lever, turns the plate D and the rock-shaft, and thereby adjusts the reel to the height required, and, releasing the latch g, the arm F re engages 85 and secures the reel in its new position. It is obvious that if it be required to move the reel a great distance upward or downward it would be necessary to move the hand-lever through a long arc, which would be inconvenient for 90 the operator. It is to overcome the necessity for this great movement of the lever that I employ the dog K. If it be required to move the reel a greater distance than can be conveniently accomplished by a single movement of the 95 hand-lever, it is only necessary for the operator to leave the arm F in engagement, as shown in Fig. 1, and, through the thumb-latch h, to release the dog K, the effect of which is to disconnect the hand-lever from the plate D and 100 permit it to be turned upward or downward, in respect to said plate, until the dog K enters

a different notch, *b*. This being accomplished, and the lever locked in a new relation to the plate D, the arm F is unlocked and the reel adjusted, as before.

5 The essence of my invention resides in the provision of means by which the relation of the hand-lever to the plate D and the rock-shaft may be changed at will by the driver in his seat, thus enabling the attendant to keep the 10 operative end of the hand-lever always in convenient position and permitting the crank-arm to be turned through an arc much greater than that traversed by the lever.

While I prefer to retain the details of construction herein shown, it is manifest that they 15 may be variously modified within the range of mechanical skill without departing from the limits of my invention. For example, the sliding dogs I and K may be replaced by any other 20 equivalent form of locking devices, of which there are many familiar to the skilled mechanic. The notches *a* and *b*, instead of being formed in a single plate, as shown, and as preferred, by reason of the greater simplicity secured, may be formed in two separate plates 25 secured to the rock-shaft. The dog I, instead of entering a slot in the upper end of the arm F, may be adapted to encircle or embrace the upper end of the arm,

30 Having thus described my invention, what I claim is—

1. The rock-shaft having a crank arm or arms to sustain the reel-shaft, in combination with the notched plate fixed thereto, the locking-arm pivoted to the frame to hold said plate 35 in different positions, the hand-lever, devices carried by the hand-lever to control the locking-arm, and devices for locking the lever to the plate in different positions, substantially 40 as described.

2. The combination, with a crank-shaft or reel-support turning on a horizontal axis, a hand-lever for adjusting the same to raise or lower the reel, means for locking the lever to the shaft in different positions, and means for holding the shaft during said adjustment of the lever.

3. The crank-shaft provided with bearings for the reel-shaft, in combination with the notched plate fixed thereto, the locking-arm pivoted to the frame and engaging said plate, the hand-lever, the dogs for locking the lever to the notched plate, and the thumb-levers mounted on the hand-lever and connected, respectively, with the dog and the locking-arm, 50 whereby the crank-shaft may be turned and fastened at will and the relation of the adjusting-lever to the shaft also changed at will.

4. The combination of the reel-supporting rock-shaft turning about a horizontal axis to 60 raise and lower the reel, the hand-lever having its end mounted loosely on said shaft, the notched plate fastened immovably on the shaft, and the spring-actuated dog carried by the lever and adapted to engage the plate, as described, whereby the lever may, at the will of the attendant and without the use of tools, be adjusted to and securely fixed in different positions in relation to the reel to maintain the lever at all times in convenient reach of the 70 driver.

In testimony whereof I hereunto set my hand, this 23d day of December, 1886, in the presence of two attesting witnesses.

WILLIAM BUTTERFIELD.
